UNITED STATES PATENT OFFICE.

ROBERT W. JESS, OF RIVERTON, ILLINOIS.

CAR-WHEEL.

SPECIFICATION forming part of Letters Patent No. 326,433, dated September 15, 1885.

Application filed July 9, 1885. (No model.)

To all whom it may concern:

Be it known that I, ROBERT W. JESS, of Riverton, in the county of Sangamon, and in the State of Illinois, have invented certain Improvements in Lubricating Car-Wheels; and I do hereby declare that the following is a full, clear, and exact description thereof, reference being had to the accompanying drawings, in which—

1c Figure 1 is a perspective view of my wheel from the outer side. Fig. 2 is a like view of the same with a portion of the hub broken away to show the interior construction. Fig. 3 is a central section upon an axial line, and 15 Fig. 4 is a section upon a line with the plane of rotation.

Letters of like name and kind refer to like parts in each of the figures.

The design of my invention is to give to a 20 car wheel and axle a maximum of efficiency and durability by insuring a constant and sufficient supply of oil to their bearing-surfaces; and to this end said invention consists, principally, in the construction of the oil-recess 25 within the hub of the wheel, substantially as and for the purpose hereinafter specified.

It consists, further, in the special construction of the wheel and its combination with the axle, substantially as and for the purpose hereinafter shown.

In the carrying into practice of my invention I employ a car-wheel, A, of any usual pattern, and within its hub a form an annular recess, a', that entirely surrounds the central bearing portion, a². The rear end of said part a² unites with and forms part of the inner end of said hub; but at its outer end the former is connected with the adjacent portion of the latter by a number of lugs or braces, a³, 35 which extend radially between said parts. The inner or axle-bearing portion, a², extends, preferably, to or near the outer face of the wheel A, while the hub proper, a, extends outward an inch or more beyond said wheel-face 40 and forms a continuation of the recess or chamber a'.

The axle B has the usual form of axle-arm, b, which is adapted to fit into the axial opening in the wheel A, with the collar b' at its 50 inner end contained within a suitable recess, a⁴, at the inner end of the hub a, and its outer end projecting sufficiently beyond the bearing

portion a² to permit of the insertion therein of a pin or key, C, that operates to lock said axle and wheel in relative positions. For the 55 purpose of enabling said key to be placed in or removed from position, the projecting portion of said hub a is provided with an opening, a⁵, which may be caused to coincide with the key-opening b² in said axle, and has sufficient size to enable said key to be passed through. Said opening a⁵ is inclosed by means of a screw-plug, D, which is closely fitted thereto and forms an oil-tight joint.

The recess or chamber a' is for the reception 65 of oil, for the introduction of which an opening, a⁶, is provided in the outer end at the center of the hub a. Said opening is inclosed by a pivoted cap or other equivalent means. From said chamber oil is permitted to pass to 70 the bearing-surface of the axle-arm b by means of a number of openings, a⁷, that pass radially through the bearing portion a² and furnish communication between the interior of the latter and said chamber.

As constructed it will be seen that the bearings of the wheel and axle-arm are surrounded by oil which cannot escape from its chamber, and by the movements of said wheel is caused to circulate freely through or between the 80 bearing-surfaces. In order to break or arrest the flow of said oil around the outer side of its chamber in consequence of centrifugal force, I provide at three or more points around the inner periphery of said chamber a' radially 85 inward-projecting flanges a⁸, which extend from the rear end of said chamber to a point upon a line with the outer end of the bearing portion a².

The wheel described is cast in one piece by 90 coring out its oil-chamber, and only requires that its axial opening, the outer end of its bearing portion a², and the collar-recess a⁴ be dressed with suitable easily-operated tools, and the openings a⁵ and a⁶ formed in order to 95 fit said wheel for use.

Having thus fully set forth the nature and merits of my invention, I claim—

1. The car-wheel A, provided within its hub a with an oil-chamber, a', which surrounds the 100 exterior and outer end of the axle-bearing a², the radial braces a³, extending between the outer end of said axle-bearing and said hub, the oil-openings a⁵, formed in said axle-bearing, and

the deflecting flanges a^8 , that project radially into said chamber, substantially as and for the purpose specified.

2. The car-wheel A, provided within the hub 5 a with the chamber a^1 , axle-bearing portion a^2 , braces a^3 , collar-recess a^4 , key and oil openings a^5 and a^6 , respectively, and flanges a^8 , in combination with the axle B, having the axle-arm b, collar b', and key-opening b², and with the

key C, substantially as and for the purpose set forth.

In testimony that I claim the foregoing I have hereunto set my hand this 6th day of July, 1885.

ROBERT W. JESS.
